Frank E. Hodges
his ATTORNEY.

UNITED STATES PATENT OFFICE

ROBERT T. WILLIAMS, OF QUINCY, ILLINOIS, ASSIGNOR TO H. M. SHEER COMPANY, OF QUINCY, ILLINOIS, A CORPORATION OF ILLINOIS

BROODER-CANOPY SUPPORT

Application filed May 27, 1927. Serial No. 194,789.

This invention relates to an improvement in brooder canopy supports.

The object of the invention is to provide supporting means for a canopy, which is attached to the stove or other form of heater used in connection with the canopy, and which permits of the canopy being adjusted up and down relative to said supporting means. The stove is preferably of the coal-burning type, although it may be of any suitable form for burning solid fuel.

The invention consists in the novel construction for attaching the canopy to its supporting means, which is connected directly to the stove, and allows the adjustment of the canopy up and down upon this supporting means. A channel-bar support has its lower end secured to a portion of the stove and is provided with a plurality of holes therein for receiving a pin formed on a bearing-ring which receives and supports the canopy, and the pin is adjustable into any of the several holes in the bar support for securing the canopy in its adjusted position relative to the stove.

The accompanying drawing is a side elevation, partly in section, showing the invention applied.

The numeral 1 represents the stove, which may be of any suitable construction, but is preferably of the coal-burning type, or of such form as to burn solid fuel. A bracket 2 is secured to the back of the stove by means of bolts or screws 3 or similar form of fastening means, and a channel bar support 4 is carried by the bracket 2 and secured thereto by the bolts 5. The channel bar support 4 is provided with a plurality of holes 6 therein at points throughout its length for receiving a pin 7 formed on the bearing-ring 8. Guide-lugs 9 are also formed on the bearing ring 8, and embrace the opposite sides of the channel bar support 4 for holding the bearing-ring in its proper relation to the support 4 during adjustment thereof longitudinally of the support.

A bearing support 10, which may be in the form of a partial ring, being open at one side, is provided with a laterally-extending flange 50 11 which is secured to, and supports, a canopy

12, and this bearing support 10 is normally seated upon the bearing-ring 8. The canopy 12 has an opening in one side thereof, normally closed by a door 13 hinged thereto as at 14. This opening is in alignment with the open side of the bearing support 10, and when the door is open the canopy may be lifted off of its bearing-ring 8 about the smoke-pipe of the stove.

The bearing-ring 8 may be adjusted longitudinally of the channel-bar support 4 by lifting the front side of this ring 8 so as to withdraw the pin 7 from its respective hole 6 in the channel-bar support 4, and the ring may then slide longitudinally of the bar, its relation to the support being limited by the guide-lugs 9. After the pin is then inserted into its proper hole, the canopy may be again seated upon the ring 8, and the door 13 closed to hold it in proper relation thereupon. The bearing support 10 is independent of the ring 8, but movably mounted thereon, so as to allow the canopy 12 to swing about the stove 1 to position door 13 properly, relative to the various parts of the stove, to gain access through this door directly to the stove for supplying fuel thereto without the necessity of removing the canopy or in any way carrying the chicks housed therebeneath.

The canopy is supported upon the ring 8 which surrounds the upper portion of the stove but is independent thereof, although it is supported by the stove through the supporting-bar 4 connected with the lower end thereof.

This forms a simple and effective means of adjustably supporting the canopy upon the heater or stove with which it is associated, while supporting the canopy independently of the top of the stove.

I claim:

1. The combination of a heater, a supporting-bar carried by the heater, and extending upwardly therefrom, said bar having a plurality of holes formed therein, a bearing-ring having a pin formed thereon in position to enter the holes for adjustably supporting the ring on the bar, guide-lugs embracing the edges of the bar for limiting the relative positions of the bearing-ring and bar, a bear-

ing-support movably mounted on the bearing-ring, and a canopy carried by said bearing support.

2. The combination of a heater, a supporting-bar carried by the heater and extending upwardly therefrom, said bar having a plurality of holes formed therein, a bearing-ring having a pin formed thereon in position to enter the holes for adjustably supporting the ring on the bar, guide-lugs embracing the edges of the bar for limiting the relative positions of the bearing-ring and bar, a bearing-support movably mounted on the bearing-ring, a canopy carried by said bearing support, said bearing support being circular and having an open side and an opening formed in the side of the canopy in alignment with the open side of the bearing support to permit of removal of the canopy.

20 3. A brooder comprising a heater, a support carried by the heater and extending upwardly beside the heater, a journal carried by the support, and a canopy rotatably supported on said journal and having a side opening therein.

25 4. A brooder comprising a heater, a canopy extending about the heater and having an opening in the top thereof permitting a circulation of air from about the heater, said opening being larger in area than the upper portion of the heater, permitting adjustment of the canopy to a point a substantial distance below the top of the heater, and means for adjustably supporting the canopy on the heater.

30 5. A brooder comprising a solid fuel heater, a support carried by the heater and extending upwardly beside the same, a journal carried by the support, means for adjusting the journal along the support, a canopy carried by the journal, and reinforcing means at the inner edge of the canopy to permit turning of the canopy on the journal, said canopy having a side opening therein.

35 45 In testimony whereof I affix my signature.
ROBERT T. WILLIAMS.
